BOILER WATER CONTROL

Application filed June 17, 1929. Serial No. 371,610.

Our invention relates to boilers of the flash or semi-flash type which have the capacity of raising a fluid ordinarily water, to the boiling point, vaporizing this fluid and usually superheating the vapor, these steps taking place continuously and consecutively as the fluid passes throughout the length of the boiler.

One type of flash boiler comprises a long tube in which these operations take place, so that a section near the intake end thereof may be considered a liquid-heating section, while a section near the throttle may be termed a superheater section, there being an evaporator section therebetween. The water is supplied to the intake end of this tube by means of a suitable high pressure pump, and the superheated steam is withdrawn from the superheater section thereof.

It is an object of this invention to provide a novel method of boiler control which may be utilized on such flash or semi-flash boilers, or on certain other types of boilers.

It is very desirable in certain boiler installations, especially those incorporated in self-propelled vehicles where the demand for power is not a constant, to be able to control the supply of water in such a manner that the pressure and temperature relations of the superheated steam at the throttle remain relatively constant. The temperature of the steam in such a boiler is, of course, a function of the output of this boiler and, upon first thought, it might seem a relatively simple solution of the problem to utilize a thermostat or other heat-responsive element in the boiler for controlling the supply of feed-water thereto.

Experiments have shown, however, that such a system of control is usually impractical and dangerous when the type of thermostats commercially available are utilized, especially if the thermostat is not positioned in the superheater section. In fact, steam temperature at the throttle, temperature at the thermostat, and boiler feed-water requirements appear to show no correlation which might be utilized in controlling the supply of feed-water to the boiler.

We have found, however, that very satis-

factory regulation may be obtained by introducing feed-water into the boiler at two or more points, one of these points ordinarily being the usual intake end of the boiler, and by controlling the supply of feed-water at these points by one or more thermostats or other heat-responsive elements positioned so as to be influenced by the boiler temperature.

It is an object of this invention to provide a method of boiler regulation or operation which utilizes a thermostat, or other heat-responsive means, set to operate at a temperature above the temperature of saturated steam in the boiler for controlling the feed-water supplied to this boiler at one or more points.

A further object of our invention is to provide a method of boiler regulation or operation wherein a plurality of thermostats, or other heat-responsive elements, is utilized for controlling the feed-water of a boiler, whether this feed-water be supplied at a single point, or at a plurality of points relatively spaced in the boiler.

Still a further object of this invention is to establish an auxiliary superheater section in the boiler, and to place a heat-sensitive element so as to be responsive to boiler temperature in this auxiliary section for controlling the admission of feed-water at one or more points. In this event another heat-sensitive element may be positioned in the main superheater section for controlling the admission of feed-water at one or more points, whether or not these latter points are the same as the former points where feed-water is admitted as a function of the boiler temperature in the auxiliary superheater section.

Further objects of this invention lie in the novel combinations of elements for performing the above outlined methods.

In steam-propelled vehicles, it is desirable to have the water pumps operated directly from the engine, which requires the use of an auxiliary pumping means receiving its energy from a separate source if the main engine is to be directly connected to the wheels of the vehicle without an intermediate transmission. In our system we provide an aux-

iliary water pump driven by an electric motor, in the control circuit of which is a speed switch controlling the operation of the auxiliary water pump as a function of the vehicle's speed, this switch acting to stop the auxiliary pump when the main pumps are driven at sufficient speed to function normally.

It is an object of this invention to provide 10 an auxiliary feed-water pump which automatically ceases to function when the main feed-water pump comes into normal operation.

Furthermore, we have found it desirable to 15 connect the auxiliary pump in such a manner that it supplies water to the boiler at one or more primary points and to connect the main pumps so that they supply water to one or more secondary points after steam 20 has been generated.

It is an object of this invention to provide primary and secondary intake points for a boiler at which points feed-water may be supplied at different instants of time.

25 It is a further object of our invention to provide two pumping systems for supplying feed water to a boiler, these systems being connected to different portions of the boiler so that the individual operation of these systems will vary the points of entrance of feed-water into the boiler.

30 A further object of our invention is to provide a system of boiler control whereby the factor of safety of tube boilers is greatly increased without sacrificing efficiency considerations.

The ordinary flash boiler has its superheater section exposed to the hottest part of the heating gas, while the evaporator and 40 liquid-heating sections are subjected to the action of the heating gas only after this gas has given up a portion of its heat to the superheater section. It thus becomes advisable to shift from the hottest portion of the heating gas, the points at which the danger of 45 tube burn-outs is highest. In other words, it is desirable to shift such points away from the superheater section.

It is an object of this invention to provide 50 a boiler control system whereby any possible danger-points in the boiler are shifted far enough down in the boiler so that the heat at such a point will be enough lower to make the chances of tube burn-outs, even under extremely low water conditions, small.

The term "boiler temperature" has been and will be used in its generic sense to include either the temperature of the contents of the boiler (steam or water temperature, 60 for instance), or to include tube temperature alone, or an intermediate temperature between steam and tube temperatures, or a temperature intermediate the fire temperature and the tube temperature. Thus, a heat-responsive element placed in the center

of the boiler tube and surrounded by steam will respond to variations in steam temperature, while if at the same time this element can receive heat directly from the tube temperature it may respond to a temperature intermediate the true tube temperature and steam temperature.

70 The embedding of the heat-sensitive element in the material forming the tube makes this element responsive only to tube temperatures, while if the element receives heat from the exterior of the tube and at the same time is exposed to the fire or heating gas, the regulation effected by the heat-responsive element will be a function of both the fire and tube 80 temperatures.

A sensitive heat-responsive element positioned so as to be affected only by steam temperature in a tube through which steam is flowing will usually respond quicker than an 85 equally sensitive heat-responsive element affected only by tube temperature. However, the danger of tube burn-outs is increased by such a system, especially when starting with a dry boiler. We have found 90 it desirable to position our heat-sensitive element in such a manner that it is affected by a temperature intermediate the tube and steam temperatures, and this invention has as one 95 of its objects a construction permitting such results as well as a system of boiler control using one or more heat-sensitive elements thus placed.

A heat-responsive element thus placed in a 100 boiler tube is affected both by steam and tube temperatures and its action may be considered to vary as a function of either the steam or the tube temperature, or as a function of both. In this latter case it should be clear 105 that in a heating system such as present in a flash boiler it is impossible for one variable (the tube temperature, for instance) to increase and the other variable (the steam temperature, for instance) to decrease at such respective rates that the net effect on the 110 heat-responsive element is nil.

Further objects and advantages of this invention will be made evident hereinafter.

Referring particularly to the drawings,—

Fig. 1 is a diagrammatic view of one type 115 of flash boiler and illustrates one of the control systems of our invention as applied thereto.

Fig. 2 is a sectional view taken on the line 2—2 of Fig. 1, and illustrates the placement 120 of the heat-responsive element in the boiler tube.

Figs. 3 to 7 inclusive graphically illustrate 125 our control system on a coordinate system wherein the peculiar thermodynamical relationships which exist are best illustrated.

Fig. 8 is a graphical representation on such a coordinate system of conditions in a boiler during starting-up operations.

As previously mentioned, the ordinary 130

type of flash boiler comprises a relatively long tube indicated by the numeral 10 of Fig. 1, this tube being enclosed in a suitable heat-resisting housing 11 and being reversed 5 upon itself in this housing in such a manner that a heating gas blown through the housing, as indicated by arrows 12, will impart to the tube 10 a major portion of the heat units contained in this gas. We have dia- 10 grammatically illustrated the tube 10 as being in the form of a helix, and have diagrammatically illustrated a burner and blower 13 or other heating device, this device being utilized to force the heating gas downward 15 through the housing 11 and into contact with successive portions of the tube 10. Ordinarily, water is supplied exclusively to the intake end 14 of the tube 10 by means of any suitable high pressure pump capable of op- 20 erating at pressures above the steam pressures generated in the tube 10.

When the water first enters the tube 10 at a temperature of T_1 , for example, this water is heated by heat conducted through the walls 25 of the lower portion of the tube 10 until this water reaches a boiling temperature T_2 corresponding to the pressure existing in the tube 10. This lower section of the tube 10 in which the water is heated to a boiling 30 temperature has thus been termed a liquid-heating section and is designated by the numeral 15 of Fig. 1.

This and succeeding changes in temperature may be best shown graphically on a coordinate system such as illustrated in Figs. 35 3 to 7 where the temperature of the contents of the boiler, whether in the form of a liquid vapor or gas, is represented by the ordinate scale calibrated in degrees F., the scale of 40 abscissas representing the percentage of total heat transmitted to the water, vapor or gas in the boiler, the zero percentage point representing the heat at the intake end 14 of the boiler, and the 100% point indicating the 45 heat at the exhaust end or throttle. Inasmuch as we are at present considering a boiler having a continuous tube in which the evaporation and the superheating takes place, 50 it follows that the abscissa scale represents to some complex scale the tube length. It is not to be assumed, however, that this scale is invariable, or even that it is a lineal function. Furthermore, it should be noted that 55 our considerations at present are limited to boiler temperature as measured only by the temperature of the contents of the boiler. This is not true in regard to Fig. 8, as will be hereinafter explained, although the 60 general type of coordinate system shown in Fig. 8 is similar to that shown in Fig. 7.

Referring now to Fig. 3, the line AE represents the rise in water temperature from T_1 to T_2 , the abscissa of T_2 being H_2 , and the 65 horizontal distance between A and E repre-

sents roughly the liquid-heating section 15 of the tube 10.

After being raised to the boiling tempera- 70 ture T_2 , evaporation takes place as heat is supplied to the boiler in sufficient quantities to furnish the heat of vaporization necessary to convert all of the water into steam. During this vaporization process, the mixture of water and steam passes through what has been termed an evaporator section 19 of the tube 10. The tube temperature in this evaporator section 19 is greater toward the throttle end of the boiler. However, the temperature of the mixture inside the tube remains substantially constant during the 75 time that the heat of vaporization is being supplied thereto. Thus, this vaporization process can be represented on the coordinates of Fig. 3 by a substantially straight line ED. Variations in pressure will cause a corresponding change in saturation temperature, 80 thus making the line ED a band under ordinary working conditions instead of a line, as shown. The error introduced through the substitution of a line for a band must be taken into account in considering thermostatic settings. We have shown this line to be substantially parallel to the base line of the coordinate system, but this showing neglects any material flow to or from the boiler. 85 Under flow conditions the pressure at the inlet end of the boiler is naturally higher than the outlet end, causing a slight drop in the 90 saturation temperature from E to D. The line ED as shown is thus a line of constant temperature, but represents increasing steam quality with increasing total heat.

At the point D, all of the water has been 95 evaporated and the resulting steam is said to be saturated, any further heat supplied acting to superheat the steam. Such a superheating action is represented by the line DF of Fig. 3, the point F lying on a vertical line 17 representing the point at which the steam is throttled as it passes through a 100 throttle 20 on its way to an engine 21 (see Fig. 1). This superheating action takes place in a main superheater section 22 of the tube 10, this section being subjected to the 105 highest temperature because of its proximity to the burner and blower 13.

Heretofore, feed-water has been invariably supplied to the tube 10 only at the intake end, this point being indicated by the arrow 110 23 of Fig. 3 which is directed toward the origin, this origin representing the intake end of the boiler tube. Attempts have been previously made to control the feed-water supplied at this point by means of a thermostat responsive to variations in temperature 115 of the superheated steam near the throttle. Such a system is illustrated in Fig. 4, which is similar to Fig. 3 except for the showing of a thermostat or other heat-responsive element positioned near the throttle and adapted 120 125 130

to shut off the supply of feed-water at a temperature below T_5 and to call for more water at temperatures above T_4 . Our experiments have shown, however, that such a system is impractical on boilers which are suitable for use in self-propelled vehicles, due to the inherent time-lag in operation of commercially available thermostats, and due to the fact that over-compensation invariably takes place even with extremely sensitive thermostats, thus making it impossible to maintain any semblance of constant pressure and constant temperature at the throttle.

Furthermore, very definite limitations exist as to the strength of the walls of the tube 10 at high temperatures and internal pressures, and it becomes necessary to limit the temperature in such a way that a safe maximum at any tube section will not be exceeded.

Tube temperature is a function not only of the temperature of the heating gas, but is also a function of the temperature of the steam therein. The higher the steam temperature the lower the heat conduction through the walls of the tube, thus giving rise to an increased tube temperature which tends to burn the metal forming the walls of the tube 10, thus decreasing the strength of the tube and increasing the danger of burn-outs. With a system of control such as shown in Fig. 4, the tube may be subjected to excessive and dangerous temperatures due to the length of the tube, for if the thermostat calls for more water, a material length of time elapses before the cooling effect of the water is felt in the main superheater section, thus making it possible for the line DF to assume some such position as GB, the point B lying above the safe limits of steam temperature to prevent tube burn-outs.

We have found that a safer control may be obtained by utilizing the thermostat for shutting off the supply of heating gas at a temperature of T_4 , as illustrated in Fig. 4. However, even with such a system over-compensation invariably exists, and conditions at the throttle are far from satisfactory.

To improve these conditions we have found it desirable to split up the feed-water supply and introduce feed-water at a plurality of different points in the boiler, so that feed-water is simultaneously introduced at different sections of the boiler instead of entering only the intake end of the boiler tube. So also, we have found it desirable to utilize a plurality of thermostats or other heat-responsive elements so placed as to be influenced by the temperatures existing at different sections of the boiler.

The system of control suggested in Fig. 5 is sometimes desirable, and comprises the use of two thermostats positioned at sections of the boiler indicated respectively by lines 28 and 29. With the thermostats thus positioned,

quite satisfactory control is obtained by supplying feed-water in varying amounts to the intake end of the boiler, as indicated by the arrow 30, and at a point in the boiler just ahead of section 29 and indicated by arrow 31. The thermostat at section 28 is responsive to variations in water temperature in the liquid-heating section of the boiler, and is adapted, when subjected to temperatures above T_5 , to call for more feed-water at point 30, and to cut off the feed-water at this point at temperatures below T_5 . In addition, we prefer to utilize this thermostat for shutting off the heat at a temperature T_{4a} somewhat above T_5 . The thermostat at section 29 is responsive to variations in boiler temperature existing in the main superheater section and is set to admit feed-water at point 31 when subjected to temperatures above T_7 , and to shut off the heat when subjected to temperatures above T_8 .

A dangerous condition with such a system might arise if the steam became superheated before it reaches the point 31 at which feed-water is introduced. Such a condition is diagrammatically shown in Fig. 5 by dotted lines HI, it being clear that the temperature of this superheated steam would be decreased when feed-water was supplied thereto at a point indicated by the arrow 31. The only protection for points in the middle of the evaporator section 19 is that afforded by the thermostat at section 28, since the thermostat at section 29 is beyond the point of water inlet indicated by the arrow 31, and is not responsive to hot points which might exist in the evaporator section. To minimize this danger we have found it sometimes preferable to divide the feed-water supplied to the point 31 and to supply a portion of this feed-water at a point indicated by the arrow 32. The temperature of the tube at this point is correspondingly lower due to this section being lower in the boiler and subjected to a heating gas of a lower temperature, so that there is less danger for superheating with its consequent decrease in tube conductivity which might result in burn-outs.

Another system of control which may be advantageously utilized in certain installations is that shown in Fig. 6 wherein a single thermostat or other heat-responsive element is positioned at a section 33 lying in the main superheater section of the boiler and positioned a distance from the throttle. This thermostat is used to control feed-water supplied at points indicated by arrows 34, 35, and 36, substantially 50% of this water entering as indicated by the arrow 34, and substantially 25% at each of the points indicated by the arrows 35 and 36.

The feed-water entering at point 36 maintains the period of operation of the thermostat relatively short and the water supplied at point 35 tends to eliminate any hot spots

existing in the evaporator section. With this system we have found it necessary to accurately position the points of feed-water inlet in order to reduce possible hot spots to a minimum. Possible danger points with this system are indicated by dotted lines JK and LM, but danger therefrom may be largely eliminated by proper regulation of the heat, and by proper placement of the points of feed-water inlet. In certain instances we have found it desirable to decrease the proportion of feed-water delivered to the boiler at the point 36 so that less than 25% is supplied at this point.

15 The preferred embodiment of our invention, however, is illustrated in Fig. 7 and also in Fig. 1, and comprises a primary thermostat or heat-responsive element 40 positioned at a section 41 of the boiler, and a secondary thermostat 42 positioned at a section 43 of the boiler, this latter section lying in the main superheater section 22. Feed-water is supplied to the intake end of the boiler as indicated by arrow 45, and to a section toward the intake end of the boiler from the primary thermostat 40, as indicated by the arrow 46, as well as to a section intermediate the two thermostats, as indicated by the arrow 47.

30 The primary thermostat at section 41 is set to call for more feed-water at temperatures above T_s , this thermostat controlling the feed-water supplied at the intake end of the boiler, as indicated by the arrow 45, and at an intermediate section in the boiler, as indicated by the arrow 46. It should be noticed that the temperature T_s lies above the saturation temperature and that this thermostat will not call for more feed-water until the steam thereadjacent is superheated. Thus, in effect we establish an auxiliary superheater section in the boiler tube which lies between the intake end and the main superheater section. The secondary thermostat 42 is set to 45 call for more feed-water at temperatures above T_{10} , this feed-water being supplied at the inlet point indicated by the arrow 47 and acting to reduce the temperature of the superheated steam in the auxiliary superheater section, just described, to saturation temperature. The thermostat 42 operates on a fairly short cycle and maintains the steam quality at the beginning of the superheater reasonably constant. The thermostat 40 operates 50 on a somewhat longer cycle determined by the distance between this thermostat and the water inlet indicated by the arrow 46.

In such a system the feed-water entering at the intake end of the boiler is heated to 60 saturation temperature at the point N, after which it is evaporated with increasing quality until reaching the feed-water inlet point indicated by the arrow 46. The feed-water supplied at this point decreases the quality 65 and reduces the steam to the saturation point

in the event that superheating has already taken place. Superheating may also take place at some point beyond the point indicated by the arrow 46, such as point O, the steam being then superheated to a point P 70 determined by the feed-water supplied at the point indicated by the arrow 47. This supply of feed-water decreases the temperature to the saturation temperature, and the steam is not again superheated until reaching some point, such as point Q, the throttle temperature being indicated by T_{11} .

We prefer to utilize either or both of the thermostats 40 or 42 for shutting off the heat at temperatures above T_{12} , so that the maximum temperature rise in the auxiliary superheater section before the heat is shut off may be indicated by RS. The only possible danger point which might exist in such a system would be due to a superheating action which might take place in the boiler tube toward the intake end from the section indicated by the arrow 46. Due, however, to the fact that such a danger point is quite low down in the boiler and the temperature of the heating gas is relatively low, the chances of tube burn-outs, even under extremely low water conditions, are small.

35 As mentioned above, Figs. 3 to 7 are based on heat-responsive elements which are responsive directly to variations in steam temperature such as might be obtainable by placing the heat-responsive elements inside the boiler tube and completely surrounded by the steam. In actual practice, however, we prefer to position our thermostats or other heat-responsive elements as indicated in Fig. 2 so that they are responsive not only to steam temperature, but also to tube temperature.

40 Referring particularly to Fig. 2, the boiler tube 10 is indicated in section and the thermostat or heat-responsive element 40 is placed therein. This element comprises an outer tube 51 through which a rod 52 passes, the tube 51 and rod 52 being of dissimilar materials having different coefficients of expansion. For most sensitive response we prefer to make the rod 52 of a material of 45 very low coefficient of expansion, such as fused quartz. It thus remains of substantially constant length, with the result that the response of the thermostat will be closely proportional to temperature changes in tube 51. The tube 51 is welded to the wall 53 of the boiler tube 10 as indicated at 54. The thermostats are thus influenced not only by the temperature of the steam passing through the boiler tube 10, but also by the temperature of the boiler tube 10, inasmuch as heat may be conducted directly from this boiler tube to the outer tube of the thermostat.

45 In Fig. 1 we have diagrammatically illustrated our preferred system of control 50

as applied to one type of boiler such as might be utilized in self-propelled vehicles. In this figure we illustrate main feed-water pumps 61, 62, and 63 directly connected to the engine 21 by a shaft 60. Each of these pumps receives feed-water from a supply line 64, the pump 61 being adapted to supply feed-water to an inlet means communicating with the intake end of the boiler, the pump 62 supplying feed-water to an inlet means communicating with the boiler tube 10 at a point corresponding to that indicated by the arrow 46 of Fig. 7, and the pump 63 communicating with the boiler tube through an inlet means positioned at a point indicated by the arrow 47 and supplying feed-water at this point. The pumps 61 and 62 with their associated inlet means provide a primary feed means for the boiler, while the pump 63 with its associated inlet means comprises a secondary feed means. The supply of feed-water to the boiler through these feed means is controlled by the thermostats 40 and 42 through primary and secondary thermostatic switches 67 and 68 which are electrically connected, in a manner to be described, to solenoid windings 69, 70, and 71 which, when individually or collectively energized, cause the pumps 61, 62, and 63 to which they are respectively connected to pump feed-water into the boiler.

We prefer to place the solenoid windings 69, 70, and 71 in controlling relationship with the intake valves of the pumps 61, 62, and 63, respectively. These intake valves may be of the ordinary poppet type actuated by a difference in pressure on the two sides thereof. This may be accomplished by a suitable armature 72 positioned in the field of influence of each of the solenoid windings so that the armature corresponding to any solenoid winding will move into engagement with the intake valve to hold this valve open when that solenoid is de-energized. The energization of this solenoid will withdraw the armature from contact with the intake valve and allow normal operation to take place. Thus, the pumps 61, 62, and 63 do not force water into the boiler until the solenoid winding associated with any particular pump is energized.

The primary and secondary thermostatic switches 67 and 68 are diagrammatically illustrated in Fig. 1. The primary thermostatic switch 67 comprises an arm 75 adapted to be held in resilient contact with the rod 52 of the primary thermostat and pivoted to a bracket secured to the outer tube 51 of this thermostat so as to be rotated in a counter-clockwise direction by a relative movement between the rod 52 and outer tube 51 such as takes place when the thermostat is subjected to increasing temperatures. The lower end of the arm is contacted by an adjusting screw 76 passing through a water-

control arm 77 formed of spring material and carrying a contact 78 which engages a contact 79 as the arm 75 is turned counter-clockwise.

Subsequently, the upper end of the arm comes into contact with an adjusting screw 80 passing through a heat-control arm 81 also formed of spring material and carrying a contact 82 which normally engages a contact 83 due to the spring of the arm 81. These latter contacts are separated shortly after the upper end of the arm 75 engages the adjusting screw 80.

The secondary thermostat switch 68 comprises a similar pivoted arm 85 which is contacted by the rod of the secondary thermostat 42, this arm being adapted, when moved in a counter-clockwise direction, to first make contact between contacts 86 and 87 corresponding to contacts 78 and 79 of the primary thermostatic switch, and subsequently to break contact between contacts 88 and 89 corresponding to contacts 82 and 83 on the primary thermostatic switch.

The separation of either of the contacts 82 and 83 or 88 and 89 breaks the circuit through a heat-control means 92 which shuts off the supply of heating gas to the boiler. One terminal of this heat-control means is connected by a conductor 93 to the contact 89, the contacts 88 and 83 being connected by a conductor 94. A return circuit to the heat-control means 92 is formed by a conductor 95 which includes a manually operable switch 96, one terminal of which is connected to a battery 97, the other terminal of which is grounded as is also the remaining terminal of the heat-control means 92.

This return conductor 95 also includes a pressure-operated switch 98, the switches 96 and 98 being in series. The switch 98 may be of any one of a number of forms known to the art and is responsive to changes in boiler pressure being usually set to automatically break the circuit through the heat-control means 92 at pressures above one thousand pounds per square inch, thus preventing a rise in pressure above the critical pressure. The switch 96 is positioned on a dash of the vehicle and is under control of the operator. The closing of this switch when the thermostatic switches are in the position shown in Fig. 1 will start a flow of heating gas through the boiler, and the opening of the switch 96 or the separation of either of the contacts 88 and 89 or 82 and 83 will stop this flow of heating gas.

The contact 82 is connected to the contact 78 by a conductor 100, there being a conductor 101 which extends therefrom to the contact 86. The contact 87 is connected by a conductor 102 to the winding 71, while the windings 70 and 69 are connected together by a conductor 103 which extends to the contact 79. The free terminals of each of

the windings is grounded, so that when the contacts 86 and 87, for instance, come into engagement, thus indicating that the thermostat 42 is calling for water, current 5 passes from the battery through the switch 96, conductors 100, 101, and 102, through the winding 71, this current returning to the battery through ground. This causes the main pump 63 to force feed-water into the 10 boiler at a point indicated by the arrow 47.

Similarly, the engagement between the contacts 78 and 79 causes current to flow from the battery through the switch 96, conductors 95, 100, 103, through the windings 15 69 and 70 and to return to the battery through ground. This causes the main pumps 61 and 62 to force water into the boiler. The amount of water forced into the boiler by any pump may be regulated by 20 suitable valves 105, 106, and 107, positioned in the inlet means respectively connected to the pumps 61, 62, and 63, or pumps 61, 62, and 63 of different capacity may be utilized.

In starting up such a boiler it is necessary 25 to supply feed-water thereto by auxiliary pumping means such as indicated by the numeral 110, inasmuch as no steam is being generated for operating the engine 21. In Fig. 1 we have illustrated this auxiliary 30 pumping means as being connected to a motor 111, one terminal of which is grounded, as indicated at 112, the other terminal being joined to one terminal of a pallet switch 113 by a conductor 114. The other contact 35 of the pallet switch is connected to the ungrounded terminal of the battery by a conductor 115. The pallet 114a is adapted to be moved upward to short-circuit the contacts of the pallet switch when the winding of a 40 solenoid 115a is energized. One terminal of this winding is grounded as indicated at 116, the other terminal being connected to a speed switch 117 through the conductor 119, and also to one terminal of a solenoid winding 45 118 which functions to allow the auxiliary pumping means to force water into the boiler when energized and to prevent this flow when de-energized in a manner previously described for windings 69, 70, and 71.

50 The speed switch 117 may be a centrifugal switch adapted to break contact when the engine 21 is operating the main pumps 61, 62, and 63 in such a manner that these pumps may function normally and supply water 55 to the boiler as previously explained.

We have found it desirable to connect the auxiliary pumping means 110 so that it supplies feed-water at the points indicated by the arrows 46 and 47, no feed-water being 60 supplied to the boiler at the intake end until the main pumps come into operation. A pipe 125 is shown as connecting the auxiliary pumping means with the inlet means at these sections of the boiler, there being valves 126 65 and 127 for controlling the relative amounts

of water entering at these two points. A branch pipe 128 extends from the feed-water supply pipe 64 and conducts feed-water to the auxiliary pumping means.

While we have shown the auxiliary pumping means 110 as communicating with the same inlet means connecting the points 46 and 47 with the pumps 62 and 63 respectively, it should be understood that this particular connection is not a necessary part of the invention. Thus, instead of utilizing the auxiliary pumping means for supplying feed-water to these sections, this auxiliary pumping means might be utilized for supplying water to one side or the other of these particular sections without deviating materially from the results obtained. The points at which feed-water is supplied from the auxiliary pumping means is not as critical as the points fed by the main pumps. 85

One of the novel features of this invention lies in the use of one pumping means supplying feed-water to one group of points in the boiler, and another pumping means supplying feed-water to another group of points in the boiler, these pumping means being utilized at different intervals of time and under different conditions of boiler operations. This is true whether or not certain points in one group are common with points in the other group. An arrangement such as this allows water to be supplied to a dry boiler during the steaming-up conditions in such a way as to protect the boiler throughout and to make large quantities of steam at normal temperature and pressure in a very short period of time. 100

The operation of the apparatus shown in Fig. 1 is as follows:

Assuming that the boiler is cold, the switch 96 is closed which energizes the heat-control means 92 and supplies heating gas to the boiler. This quickly heats up the tube 10, especially that portion of the tube 10 in the superheater section 22, due to the fact that no water or steam is present inside the tube. Furthermore, the secondary thermostat 42, receiving heat directly from the boiler tube, is very quickly heated so as to close the contacts 86 and 87, thus supplying current 105 through these contacts, as previously mentioned, and through the solenoid windings 116, 70, and 71. 110

Due to the fact that the engine is not turning the main pumps are not operated and the energization of these solenoid windings does not affect the feed-water supply to the boiler. Current, however, flows from the conductor 102 through the speed switch 117, which is at this time closed, and energizes the solenoid winding 115a. This closes the pallet switch and energizes the motor 111, current flowing through the conductors 115, 114, and 112. The auxiliary pumping means 125 thus supplies feed-water at points indicated 130

by the arrows 46 and 47, preferably, although not invariably, in equal amounts. The boiler tube at these points being already hot, this feed-water is almost immediately turned 5 into steam, and when the pressure in the tube 10 builds up sufficiently the opening of the throttle 20 will start the engine 21, thus driving the main feed-water pumps 61 to 63. In the event that the throttle is not opened, 10 the temperature will continue to build up in the boiler and the contacts 88 and 89 will separate at a temperature corresponding to T_{12} in Fig. 7 at which time the supply of heating gas is cut off.

15 As soon as the vehicle starts to move, the main feed-water pumps 61, 62, and 63 start to operate. The capacity of these pumps may not be high enough to immediately force adequate quantities of feed-water into the 20 boiler for normal operation until the vehicle has attained more speed. In the meantime, the auxiliary pumping means 110 continues to supply feed-water to the boiler until such a time as the vehicle is travelling fast 25 enough to open the speed switch 117. As previously mentioned, this switch is not opened until the main feed-water pumps 61 to 63 are functioning normally and the speed of the vehicle is sufficient to cause 30 these pumps to force adequate quantities of feed-water into the boiler. When the speed switch 117 opens, the motor 111 is de-energized, thus stopping the auxiliary pumping means until such a time as the velocity of 35 the vehicle is lower than the velocity at which the speed switch 117 is set to operate.

This sequence of operations may also be 40 illustrated on a coordinate system such as shown in Figs. 3 to 7 inclusive. Thus in Fig. 45 8, we have diagrammatically illustrated the sequence of events in the boiler during steaming-up operations. In considering Fig. 8, it should be particularly noted that the temperatures plotted thereon are the temperatures to which the thermostats are responsive in the preferred form of our invention. In other words, the temperatures illustrated in Fig. 8 correspond to some temperature intermediate the true steam temperature and the 50 true tube temperature.

Assuming that the boiler is dry, and that 55 heating gas is being supplied to the boiler, curve U indicates the rise in the intermediate temperature mentioned above which takes place throughout the length of the boiler tube 10. Curve V illustrates conditions at a subsequent instant and shows a rise in temperature over that indicated in curve U. It will be noted that curve V intersects section 60 43 at a point above T_{10} so that the thermostat 42 calls for water. The auxiliary pumping means is thus energized, as previously explained, and feed-water is supplied at points indicated by the arrows 46 and 47. This 65 supply of feed-water at these points greatly

decreases the temperature of both the tube and the steam, thus giving rise to a temperature curve similar to that illustrated by the letter W. Curve X shows a rise in temperature throughout the boiler, and passes through T_{10} so that the thermostat 42 calls for more water. The auxiliary pumping means is still operating so that at least a major portion of the feed-water is supplied to the sections indicated by the arrows 46 and 47. Curve Y illustrates the beginning of steam flow when the throttle is cracked, while curve Z illustrates additional flow. By this time the vehicle is moving and the speed switch 117 opens. Feed-water is at this time being supplied to the main feed-water pumps 61, 62, and 63 to the sections indicated by the arrows 45, 46, and 47 previously described. The full-line curve A₁ shows the beginning of normal operation, both the thermostats 40 and 42 calling for water. We have shown the curve A₁ as crossing the section 41 above the temperature T_{12} , thus shutting off the supply of heating gas in a manner previously described.

Another very successful and slightly different method of control has been found wherein the water inlet at the point indicated by the arrow 46 has been eliminated. In this case the primary thermostat 40 may be positioned somewhat closer to the inlet end of the boiler, and may be adjusted to call for water at slightly lower temperatures, in order to properly protect the tubes of the evaporator section. As a rule the elimination of water inlet at the point indicated by the arrow 46 will cause the primary thermostat 40 to operate on a longer cycle.

It should thus be apparent that by splitting up the feed-water supply, and controlling this supply by a plurality of thermostats we achieve not only safer boiler operation, but a decrease in the time necessary for generating steam. Furthermore, with such a system of control the temperature and pressure relationships at the throttle may be maintained relatively constant.

While we have illustrated a plurality of main feed-water pumps directly connected to the engine 21 and controlled by solenoid windings operatively connected to the intake valves of these pumps, we are not limited to this combination. If desired, a single pump of large capacity may be utilized, and the solenoid windings 69 to 71 utilized for controlling the opening of a plurality of valves positioned in branch lines extending from this pump to the different sections in the boiler at which it is desired to introduce feed-water. Furthermore, if desired the solenoids 69 to 71 may be utilized for operatively connecting the engine and the main feed-water pumps without departing from the spirit of this invention.

While the positioning of each thermostat

relative to the walls of the boiler tube is an important detail of this invention inasmuch as it permits very accurate and sensitive control of boiler conditions, nevertheless the 5 utility of our invention is not predicated upon this feature for obviously thermostats responsive only to steam temperature or tube temperature might be used in combination with a plurality of water inlet means or in combination 10 with other of the novel features and steps herein disclosed.

We claim as our invention:

1. In combination: a boiler adapted to produce steam; a steam-operated pumping system 15 actuated by the steam generated by said boiler for supplying feed-water to said boiler at a plurality of sections; and an auxiliary pumping system for supplying feed-water to only a portion of said sections.

20 2. In combination in a self-propelled vehicle: a boiler; an engine adapted to be driven by steam produced by said boiler; a main pumping system operated by said engine and adapted to supply feed-water to said boiler 25 when said vehicle is in motion; an auxiliary pumping system for supplying feed-water to said boiler when said vehicle is stationary; and a speed-controlled device for rendering said auxiliary pumping system inoperative 30 when said vehicle has reached a sufficient speed to cause said main pumping system to adequately supply said boiler with feed-water.

35 3. In combination with a boiler of the flash or semi-flash type having a main and an auxiliary superheater section: a primary heat-responsive element responsive to changes in boiler temperature in said auxiliary superheater section; a secondary heat-responsive 40 element responsive to changes in boiler temperature in said main superheater section; primary feed means adapted to supply feed-water at a section toward the intake end of said boiler from said primary heat-responsive element; secondary feed means adapted to supply feed-water to said boiler at a point intermediate said primary and secondary heat-responsive elements; primary means controlled by said primary heat-responsive element and adapted to control the flow of feed-water 45 passing through said primary feed means; and secondary means controlled by said secondary heat-responsive element and adapted to control the flow of feed-water 50 passing through said secondary feed means.

55 4. In combination with a boiler of the flash or semi-flash type having a main and an auxiliary superheater section: a primary heat-responsive element responsive to changes in boiler temperature in said auxiliary superheater section; a secondary heat-responsive element responsive to changes in boiler temperature in said main superheater section; primary feed means adapted to supply feed- 60 water to the intake end of said boiler and to a

section between said intake end and said primary heat-responsive element; secondary feed means adapted to supply feed-water to said boiler at a point intermediate said primary and secondary heat-responsive elements; primary means controlled by said primary heat-responsive element and adapted to control the flow of feed-water passing through said primary feed means; and secondary means controlled by said secondary heat-responsive element and adapted to control the flow of feed-water passing through 70 said secondary feed means.

In testimony whereof, we have hereunto set our hands at Los Angeles, California, this 80 13th day of June, 1929.

BRUCE BURNS.
